US0D1029815S

(12) **United States Design Patent** (10) Patent No.: **US D1,029,815 S**
(45) Date of Patent: ** Jun. 4, 2024

(54) **DISPLAY MODULE**(71) Applicant: **Samsung Display Co., LTD.**, Yongin-si (KR)(72) Inventors: **Jun-Sang Lyu**, Seoul (KR); **Jun Yong Park**, Seoul (KR); **Ho-Seok Han**, Cheonan-si (KR)(73) Assignee: **Samsung Display Co., Ltd.**, Yongin-si (KR)(**) Term: **15 Years**(21) Appl. No.: **29/869,901**(22) Filed: **Jan. 11, 2023****Related U.S. Application Data**

(62) Division of application No. 29/647,773, filed on May 15, 2018, now Pat. No. Des. 978,847.

(30) **Foreign Application Priority Data**

Feb. 2, 2018 (KR) 30-2018-0005969

(51) LOC (14) Cl. **14-03**

(52) U.S. Cl.

USPC ..... **D14/248**; D14/250; D14/432(58) **Field of Classification Search**
